(57) **CLAIM**

The ornamental design for a trigger guard, as shown and described.

DESCRIPTION

FIG. 1 is an upper, front, and left-side perspective view showing the new design;

FIG. 2 is an upper, rear, and left-side perspective view thereof;

FIG. 3 is a lower, front, and left-side perspective view thereof;

FIG. 4 is a lower, rear, and left-side perspective view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a top plan view thereof;

FIG. 10 is a bottom plan view thereof; and,

FIG. 11 is a rear perspective view thereof shown in an environment of use.

The broken lines in FIGS. 1-6, 9, 10, and 11 depict portions of a trigger guard that form no part of the claimed design. The broken lines in FIG. 11 depict environment that forms no part of the claimed design.

1 Claim, 8 Drawing Sheets
